UNITED STATES PATENT OFFICE.

FRANZ A. BOEDTCHER, OF BERGENFIELD, NEW JERSEY.

DOOR-OPENING DEVICE AND LOCK FOR ELEVATOR-DOORS.

1,400,721.

Specification of Letters Patent. Patented Dec. 20, 1921.

Application filed January 17, 1919. Serial No. 271,614.

To all whom it may concern:

Be it known that I, FRANZ A. BOEDTCHER, a citizen of the United States, residing in Bergenfield, county of Bergen, and State 5 of New Jersey, have invented a certain new and useful Door-Opening Device and Lock for Elevator-Doors, of which the following is a specification.

The objects of my invention are to provide 10 a device of the class in which the door of an elevator shaft is securely locked unless the car is abreast of the door in which event the door may be opened by suitable mechanism available to the car operator; to provide 15 an automatic lock, associated with the controller handle of the car-operating mechanism, whereby shifting of the handle is precluded while the door is open; and to provide emergency means for opening the 20 elevator shaft door when the car is not present.

Features of the invention other than those specified will be apparent from the herein-after detailed description taken in conjunction 25 with the accompanying drawings.

In the accompanying drawings, I have illustrated one practical form of the invention, but the construction shown therein is to be understood as illustrative only, and 30 not as defining the limits of the invention.

Figure 1 is an inside view of my improved lock installed in the upper part of a door of an elevator shaft;

Fig. 2 shows the door opening means connected to an elevator car, together with the controller locking mechanism;

Fig. 3 shows a door opening means for an elevator shaft door which is suitable for emergency use;

Figs. 4 and 5 show the locking mechanism which connects the opening device with the controller, Fig. 4 showing the device with the controller locked, and Fig. 5 in a position in which the controller is not interfered with, but the door opening mechanism is locked; and

Figs. 6 and 7 are sectional views of portions of the locking device, Fig. 6 being a longitudinal section and Fig. 7 a cross section.

My improved safety device is composed of an elevator car attachment 1, and an elevator well door attachment 2 which are adapted to co-operate so as to preclude the door from 55 being opened except when the elevator is abreast of it, and, also, to preclude the

movement of the elevator except when the door is closed, and locked.

For convenience, the elevator attachment will be described first. This attachment 1 60 is provided at its top with two rails, an upper 3 and a lower 4, which run over the entrance of the elevator and carry between them a suitable cross head 5, preferably a ball bearing cross head or hanger 5, and to 65 this is secured the parallel guides 6 which are vertically disposed and adapted to engage a corresponding pin 7 on the lock 2, which will hereinafter be described. It is sufficient to state here that these guides always remain parallel and move with the cross head 5, carrying the pin 7 between them throughout such movement so as to shift the elevator shaft door and open or close the same, as well as to lock or unlock 75 it. One of these guides 6 has a link 7', pivoted thereto, which is also pivotally connected to a bell crank lever 8 by means of a pivot 9 and a pin 10 which is adapted to engage the extension of the link 7' and hold 80 the same when in alinement with the main arm of the bell crank lever 8, but not prevent the movement of the link 7' to the position shown in dotted lines in Fig. 2. The lower end of the lever 8 is secured to a bracket 85 11 which is pivotally mounted at 12 in the car 13, and at the front thereof and near the floor at any convenient place. The lower end of the lever 8 carries a pedal 14 and a pivot 15 which is connected to an upright rod 90 16 running to the lock 17. This lever secures the controller 18 when the rod 16 is lowered, and rails 6 in a retracted position. It also serves to lock the lever 8 against movement, when the controller 18 is operated. The mechanism by which this is accomplished will now be described.

The lock 17 is provided with a suitable casing 19, preferably rectangular as shown, and provided at its bottom and top with 100 suitable slots through which the rod 16 may slide. Near the bottom is a pivot 20 on which is mounted a rocker 21 which is normally kept rocked away from the rod 16 by a suitable coil spring 22, the upper end 105 of which is secured to the rocker and its lower end to the casing, as shown. The rocker 21 has fixed thereto a suitable arm 23 pivotally connected to a link 26 which is, in turn, pivotally connected to the handle 110 27 of the controller 18.

The rod 16 is provided with a shoulder 28

(see Fig. 6), adapted to ride over the curved surface of the rocker 21 and when it does so ride it obviously cannot be lowered. Now when the handle 27 is shifted one way or 5 the other, as shown in Fig. 5, the link 23 is pulled down by the link 26 connected to handle 27, thereby pulling the rocker under the shoulder 28 against the tension of the spring 22. This locks the rod 16 against a 10 downward movement and clockwise oscillation of the bell crank 8 is thus precluded. Accordingly, the bell crank cannot operate to open the door when the controller is in a position to cause movement of the car. 15 However, when the controller is in a neutral position and the car at rest, the plate 21 will be moved to the position shown in Figs. 2 and 4 wherein it will be out of the path of travel of the shoulder 28 of the rod 16. 20 Now, when pressure is put on the foot pedal 14, it throws the upper part of the bell crank lever 8 to the right of the position shown in Fig. 2, and the rod 16 is simultaneously drawn downwardly, thereby preventing the 25 rocker 21 from swinging to the right in this figure. The result is that the handle 27 cannot be shifted, for the reason above given, and the car cannot move because the controller 18 cannot operate. To raise the 30 arm 16 so that the controller can operate, the hand of the operator may be placed on the upper part of the bell crank lever 8 and the cross head 5 shifted to the left by these means or he may take his foot from the 35 pedal 14 and place it on a second pedal 28' on a lever 29, pivoted at 30 near the floor of the car 13, and provided with a suitable link connection 31 with the pivot 15. Lever 29 is so arranged and disposed that pressure on the pedals 28' will raise the bar 16. Bar 16 may be guided by the walls of 40 the case 19, but the preferred method is to guide it by means of a bracket 32, mounted on a suitable bolt 33 set in the back of the casing 19 and provided with a coil spring 34 (see Fig. 7), so that rod 16 may be properly guided at all times. Coil spring 34 encircles a bolt 33 and is positioned between the head of the bolt 33 and the bracket 32 45 and normally serves to force the bracket against a flat bearing block positioned immediately behind the same. However, the hole in the bracket 32, through which the pin 33 passes is slightly larger than said bolt to allow of the bracket being rocked laterally on the bolt by means of a small handle 24. The spring 34 normally maintains the bracket in a fixed position, but in case of 50 injury to any part of the working mechanism, due to accident or other unforeseen cause, the handle 24 may be operated upon as a push button to force one end of the bracket back and the opposite end of the bracket forward. This operation will cause 55 the rod 16 which is in the embrace of the

bracket to be shifted forward and out of the path of the rocker 21 so that the controller may be operated to allow the car to proceed even though the door is not closed and locked. It will be understood, that this however is for emergency cases only, and the operation of the bracket in the manner described is normally precluded through the covering of the lock box 17 by a glass plate 25. While this plate normally covers the 75 working parts and precludes their operation, it may be readily broken in case of accident to allow of movement of the car which would otherwise be rendered impossible with the safety appliances embodied in 80 this invention.

It is noticeable in this regard, that the releasing mechanism specified is accessible to the operator at all times and the necessity for crawling out under the car or on top of 85 the car, as generally has heretofore been the case, is entirely obviated by this invention.

The door 35 of the elevator shaft is hung in the usual manner, or in any suitable manner, as by rollers 36 which travel on a fixed 90 track 37 of the usual kind, secured to wall 38 of the shaft. Mounted on door frame 39, near the closed position of the door, is a suitable bracket 40 with an upwardly extending lug 41 which engages the corresponding recess within a detent or latch 42 provided with a beveled face 43 adapted to ride over the lock 41 when the door is closed. When this door is closed the latch 41 rests in a corresponding recess adjacent to the 95 beveled portion 43 and a pivot 44 mounted on a plate 45 which is secured to the door 35, permits a swinging movement of the latch which is sufficient to enable it to accomplish this purpose. The upper end of the latch 42 is provided with a coil spring 46 which engages a swinging lock arm 47, which, at its upper end, carries the pin 7 and near its lower end it is pivoted on a pin 48 on plate 45. Lock 47 also carries a projection 49 100 which is adapted to abut against a corresponding part of the latch 42 and secure the same so that it cannot be swung until the lock 47 is moved about its pivot, whereupon the latch is pulled by the spring 46 so as to release the lug 41 as the door 35 is shifted on the track 37. This occurs when the guides 6 engage the pin 7, as above described.

There are times when the elevator is not 120 level with door 35, and yet it may be desirable to open this door. This is accomplished in one embodiment of my invention by providing the lock 47 with an additional extension 50 which is opposite the extension 125 49 and provided with a chain 51 which enters a guide 52 which extends from near the top to near the bottom of the door 35. The chain 51 is provided near its lower end with a ring 53, which is preferably placed in a 130

glass, emergency case 54 which may be broken from the front of the door 35 or may be viewed from the front of this door and opened directly from the rear of the door.

5 This emergency opening device may be used at any time by simply grasping the ring 53 and pulling it down, and this will have the same effect as engaging the knob 7 and pulling it as above described.

10 In view of the foregoing, the operation of my improved device will be readily understood. Assuming that the parts are as indicated in Figs. 1 and 2, and that the elevator is raised until the guides 6 come

15 in proper contact with the knob 7 and that the elevator is at the proper level and at rest with the controller handle 27 in a vertical position; the operator then places his foot on the pedal 14 and thereby lowers the

20 rod 16 and locks the rocker 21 in position, while at the same time the bell crank lever 8 swings the cross head 5 so as to open the door 35, as described above. If desired, the operator may swing the bell crank lever 8

25 by hand, either way, or he may open the door by the foot pedal 14 and close the same by the foot pedal 28'. In any event, he closes the door by swinging the cross head 5 to the left and then the door closes until

30 the latch 42 engages the projection 41, whereupon the door is locked and held secured by the lock 47 behind the latch 42. At the same time the bar 16 is raised by the bell crank lever 8 and then the controller 27

35 may be manipulated in the conventional manner to operate the car. When the handle 27 is shifted, the opening device is locked as above described.

It will be understood that mechanical and 40 formal changes may be made in the structure described, such as the substitution of equivalents, without departing from the spirit or substance of the invention, the scope of which is commensurate with the

45 appended claims.

What I claim as new and desire to secure by Letters Patent is:

1. In a device of the class described, a shaft door, means for normally locking the 50 door in closed position, an elevator car, a controller for operating the car, and means, carried by the car, for operating the door locking means of the shaft door when the car is in position at the floor, said lock 55 operating means embodying lock engaging means adapted to automatically engage the lock when the car arrives at the floor, a foot operated lever for operating said lock engaging means, and operative connections

60 between the lever and the car controller for automatically precluding the operation of the lever while the controller is in a position to effect the operation of the car, and for automatically precluding the operation 65 of the controller when the lever is in any

other position than that which corresponds to the closed and locked position of the shaft door.

2. In a device of the class described, an elevator shaft having a door provided with 70 a lock, an operating projection extending from the lock, a car provided with a door opening, a controller on the car for controlling the operations thereof, and guides mounted on the car for bodily movement 75 and adapted to engage with the projection of the lock, in combination with a bell crank lever for bodily shifting the guides to unlock and open and close the door, and means operated by the bell crank for locking the 80 car controller against operation, while the door is fully or partially open.

3. In a device of the class described, an elevator shaft with a door mounted therein, a lock for said door, a projection extending therefrom, an elevator car with movable guides mounted thereon which are adapted to engage the projection on said lock, a cross head for supporting said guides and means for supporting said cross 90 head, a bell crank lever and link connection for shifting said cross head, a controller with a handle extending therefrom, a link connected to said handle, a rocker and means for mounting the same for supporting said arm, and a vertically disposed rod adapted to engage said rocker and hold the same so that the arm will be in an elevated position and means for connecting said rod to said bell crank lever. 100

4. In a device of the class described, an elevator shaft with a door mounted therein, a fixed projection secured to said shaft, a latch pivotally mounted on said door and adapted for engagement with the fixed projection, a lock adapted to secure said latch in a place so that the door cannot be opened without shifting the lock, an elevator car, and means mounted thereon for shifting said lock and opening said door. 105

5. In a device of the class described, an elevator shaft provided with a floor door, a fixed keeper, a latch pivotally mounted on said door and adapted to engage with the keeper to lock the door in closed position, 115 and means for locking the latch in engagement with the keeper, in combination with an elevator car, means mounted on the car for opening and closing the door, while the car is at rest at the floor, said means serving 120 also to actuate the lock to lock and unlock the latch.

6. In a device of the class described, a pair of tracks, a cross head mounted between said tracks, guides carried by said cross head, 125 a car for supporting said tracks, a link connected to said guides, and manually operated a lever pivoted in said car and connected to said link for shifting said guide.

7. In a device of the class described, an 130

elevator shaft provided with a shaft door, an elevator car operable in said shaft, shaft door opening means mounted on the car and embodying a manually operable lever, a rod, 5 provided with a shoulder, associated with the door opening lever, a car controller, a spring controlled rocker operatively connected to the controller and adapted to rest against the shoulder of the rod when the 10 controller is in a position to effect movement of the car, whereby the lever is locked against operation so long as the car is moving, said lever serving to shift the rod into the path of the rocker when the former is 15 operated, while the car is at rest, to lock the controller against movement until the door is again closed.

8. In a device of the class described, a shaft door, means for normally locking the 20 door in closed position, an elevator car operable in the shaft, a controller for controlling the operations of the car and means carried by the car for operating the door locking means to the shaft door when the car is in 25 position at the floor, said door operating means embodying lock engaging guides adapted to automatically engage the lock when the car arrives at the floor, a foot operated bell crank lever for actuating the guides 30 to lock and unlock, and open and close the door, and locking connections between the bell crank lever and the car controller whereby the car controller is locked against 35 operation when the door is fully or partially open and the bell crank lever is locked against operation when the car controller is in the position to effect movement of the car.

9. In a device of the class described, an elevator car with door opening means 40 mounted therein, a vertically disposed rod with a shoulder running from said door opening means, a spring controlled rocker adapted to rest under the shoulder in said rod when the same is elevated, a car controller and means connecting the rocker and the car controller so that the car controller cannot be shifted when the rod is lowered and the rod cannot be lowered when the car controller is being shifted.

50 10. An elevator door lock embodying a fixed projection adapted to be secured to a door casing, a latch pivoted to the associated door and shaped to engage with the fixed

projection, and a locking member also pivoted on the door and normally engaging 55 with the latch to lock the latch against disengagement from the fixed projection, in combination with an operative connection between the locking member and the latch, whereby when the locking member is operated to release the latch, the latch is operated to disengage the fixed projections and permit of the opening of the door.

11. An elevator installation embodying an elevator car, and an elevator shaft in which 60 the car is adapted to travel and which shaft is provided with floor doors, in combination with a fixed projection mounted on the shaft adjacent a floor door, a latch pivoted to the associated floor door and shaped for engagement with the fixed projection, a locking member also pivoted on said floor door and adapted to normally engage with the latch to maintain the latch in a position to lock the door closed, means carried by the 65 elevator car and adapted to engage with the locking member, when the car is at rest at a floor, to permit of the operation of the locking member from interiorly of the car, and connections between the locking member 70 and the latch to effect disengagement of the latch from the fixed projection when the locking member is retracted.

12. An elevator installation embodying an elevator car, an elevator shaft in which the 75 car is adapted to travel and which shaft is provided with a floor door, locking mechanism for normally locking the floor door in position, auxiliary locking mechanism operable from within for normally precluding 80 the unlocking of the door until the car is at rest at the floor.

13. An elevator installation embodying an elevator car, an elevator shaft in which the 85 car is adapted to travel and which shaft is provided with a floor door, latch mechanism for normally retaining the door in closed position, means for locking the latch mechanism against operation, and means carried 90 by the car and operable to release the latch and permit of the opening of the door when the car is at rest at the floor.

In testimony whereof, I have signed my name to this specification.

FRANZ A. BOEDTCHER.
